US00D776681S

(12) **United States Design Patent** (10) **Patent No.:** **US D776,681 S**
Mariet et al. (45) **Date of Patent:** **** Jan. 17, 2017**

(54) **DISPLAY SCREEN OR PORTION THEREOF WITH GRAPHICAL USER INTERFACE**

(71) Applicant: **Google Inc.**, Mountain View, CA (US)

(72) Inventors: **Robertus Christianus Elisabeth Mariet**, Sunnyvale, CA (US); **Manuel Christian Clement**, Felton, CA (US)

(73) Assignee: **Google Inc.**, Mountain View, CA (US)

(**) Term: **15 Years**

(21) Appl. No.: **29/537,066**

(22) Filed: **Aug. 21, 2015**

Related U.S. Application Data

(62) Division of application No. 29/438,651, filed on Nov. 30, 2012, now Pat. No. Des. 739,423.

(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of an image of a display screen or portion thereof with graphical user interface according to our design.

The broken line showings of portions of a display screen, text, and other features in the figures are environmental only and form no part of the claimed design.

1 Claim, 1 Drawing Sheet
